[57] **CLAIM**

The ornamental design for a display base for spheres, as shown and described.

DESCRIPTION

FIG. 1 is a perspective view of a display base for spheres showing my new design, the broken line showing of the plaque for illustrative purposes only;

FIG. 2 is a top plan view thereof;

FIG. 3 is a side elevational view thereof, all sides being identical;

FIG. 4 is a cross-sectional view thereof, taken in the direction of the arrows along line 4—4 of FIG. 2; and,

FIG. 5 is a reduced side elevational view thereof, the basketball shown in broken lines for illustrative purposes only.

My design has a resemblance to a stubby truncated pyramid having a square base and having a large shallow concave depression in its upper planar surface.
